(57) **CLAIM**

The ornamental design for a beam projector, as shown and described.

DESCRIPTION

FIG. 1 is a top perspective view of a beam projector, showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is a back perspective view thereof;
FIG. 9 is an enlarged view of the encircled portion 9 in FIG. 1;
FIG. 10 is an enlarged view of the encircled portion 10 in FIG. 2;
FIG. 11 is an enlarged view of the encircled portion 11 in FIG. 2; and,
FIG. 12 is an enlarged view of the encircled portion 12 in FIG. 4.

The even-dash broken lines illustrating portions of the beam projector form no part of the claimed design. The dot-dot-dash broken lines encircling enlargement portions of the claimed design form no part of the claimed design.

1 Claim, 12 Drawing Sheets
